UNITED STATES PATENT OFFICE

JEAN JOSEPH CHARLES LAROZE, OF ST. CLOUD, FRANCE, ASSIGNOR TO THE FRENCH SOCIETY "LA ROUE ELASTIQUE," OF BILLANCOURT, SEINE, FRANCE

FLEXIBLE WHEEL

Application filed December 1, 1928, Serial No. 323,024, and in Germany December 10, 1927.

The present invention relates to flexible wheels.

One of the objects of the invention is to interpose a resilient system between the hub and the rim of the wheel in such a manner that the strain (in said system) tends to be uniformly distributed irrespective of the point at which pressure is exerted on the rim.

Other objects will appear in the course of the detailed description now to be given with reference to the accompanying drawings, in which:—

Fig. 1 is an elevation partly in section of one constructive embodiment of the invention;

Fig. 2 is a section taken on line 2—2 Fig. 1;

Fig. 3 is a view similar to Fig. 1 illustrative of the position of the various operative elements during deformation of the rim;

Fig. 4 represents, in elevation and partly in section, a second form of the invention.

Fig. 5 is a section taken on line 5—5 of Fig. 4;

Fig. 6 illustrates, in elevation and partly in section, a third form of the invention;

Fig. 7 is an elevation partly in section of a fourth illustrative embodiment of the invention; and

Fig. 8 is a section taken on line 8—8 of Fig. 7.

Referring to Figs. 1 to 3 of the drawings, there is shown a hub *a* adapted to be mounted on an axle *b*,—a support for the spokes consisting of a pair of lateral plates *c*¹, *c*¹ rigidly connected to the hub, a peripheral cylindrical plate *c*² having spoke openings *c*⁰ therethrough, and a series of fixed shafts *d* supported by plates *c*¹, *c*¹,—arms *e* pivotally supported on shafts *d*,—spokes *h* articulating at *f* with arms *e*,—a rim assembly pivotally connected to spokes *h* by pins *i* and consisting of a rim support *i*¹, a pair of thin steel rims *k*¹, *k*² rigidly connected to support *i*¹, and a rubber rolling surface *k*,—and a resilient shock-absorbing system consisting of a series of pulleys *d*¹ and *f*¹ loosely mounted on shafts *d* and pins *f* respectively so that they do not interfere with the free movement of arms *e* and spokes *h*, and a pair of rubber or similar

resilient bands *l*¹ mounted in the grooves of said pulleys.

From the foregoing, it will be seen that, when one spoke *h* is forced inward (Fig. 3), the remaining spokes divide the total impact 55 and tend to maintain a substantially circular form for those parts of the rim not in contact with the ground.

In the form of wheel illustrated in Figs. 4 and 5, the general assembly remains the same 60 except for the resilient shock-absorbing system which is here composed of a series of T-shaped elements *m* having their inner extremities tied together, a series of springs *l*² and opposite arms of the T hooked over pivot pins *d* and *f*, springs *l*² forming a ring having substantially the same function as bands *l*¹ in Figs. 1 to 3.

The structure shown in Fig. 6 differs from those already described only in the form of 70 resilient shock-absorbing system. Pivots *f*, instead of reacting on resilient elements of the type of *l*¹ in Figs. 1 to 3, or of *l*² in Figs. 4 and 5, are urged inwardly by a series of 75 chains or cables *n* fastened centrally to a movable drum *o* which is supported concentrically with hub *a* and reacts thereon through the intermediary of a compression spring *l*³ abutting against stops *p* and *p*¹ integral with elements *a* and *o* respectively. Obviously, this 80 form of wheel functions in a manner similar to those already described.

In the device represented in Figs. 7 and 8, the spokes are formed in telescoping sections *r*¹ and *r*². The shortening effect on any single 85 spoke *r*¹, *r*² produced by a peripheral shock, is transmitted by a chain or cable *n* passing through a ring *u* rigidly attached to section *r*² and to a pair of drums *t*¹ and *t*² rotatably mounted on hub *a* and reacting against one 90 another through a spring *l*³ bearing against stops *p* and *p*¹ integral with *t*¹ and *t*² respectively, a compensating spring *t*⁴ being inserted between said stops to reinforce the action of spring *l*³. It is obvious that cable 95 or chain *n* may be fixed at *u* instead of passing therethrough. In this form of wheel, the spokes are, as in the wheels already described, pivotally connected to the rim assembly at *i*, and sections *r*¹, *r*² of each spoke tend to re- 100

main in extended relation under the action of flexible rim k , k^1 , k^2 . It is to be understood that only 4 spokes have been shown merely to simplify the drawing but that a larger number should be used.

5 5. What I claim is:—

- 10 1. A wheel comprising a rim assembly including a substantially circular elastically deformable rim element, a plurality of spokes connected to said rim assembly, said spokes having a portion thereof which is displaceable radially, and means operative to oppose the outward displacement of all but one spoke, when the displaceable portion of said 15 last-named spoke is displaced inwardly.
- 20 2. A wheel comprising a rim assembly including a substantially circular elastically deformable rim element, a plurality of spokes connected to said rim assembly, said spokes having a portion thereof displaceable radially, and a resilient assembly operative to oppose the outward displacement of all but one spoke when the displaceable portion of said last-named spoke is displaced inwardly.
- 25 3. A wheel comprising a rim assembly, spokes pivotally connected to said rim assembly, a hub-assembly including a plurality of fixed pins, arms pivotally mounted on said pins, each arm having its free extremity pivotally connected to a spoke, and a resilient assembly operative to exert a centripetal pull on the points connecting the arms to the spokes.

30 In testimony whereof I have signed this
35 specification.

JEAN JOSEPH CHARLES LAROZE.
